ROTARY SWITCH

Hans P. Luhn, Armonk, N. Y., assignor to International Business Machines Corporation, New York, N. Y., a corporation of New York

Application May 6, 1948, Serial No. 25,484.

2 Claims. (Cl. 200—11.)

1

This invention relates to electrical units and particularly to a novel method and process of construction of a unit.

The unit disclosed herein is employed as an electrical instrumentality in an electric accounting machine and is known in the art as a commutator readout unit or an impulse distributor, depending upon its function. When used as an emitter, it is used as a source means to transmit timed digit representing impulses and, when used as a digit readout, it determines the digit representing impulses to be transmitted. Such functions are conveniently exemplified in the C. D. Lake et al. Patent 1,976,617, granted October 9, 1934. The thickness of such units was not of importance in the machine of this patent, but at the present time it is of prime importance in the construction and design of present commercial electrical accounting machines, particularly since the time of the patented machine the denominational orders of such units have increased to such a number that an accounting machine would be inadvertently large if units previously devised were employed. While the present unit is devised as a solution to the above problem, its incorporation is not necessarily confined to this form of machine and may answer the requirements for the design of a similar unit in any other form of machine.

It is the broad object of the invention to devise an electrical commutator unit which is practical in fabrication and relatively thin, so that a number of such units may be assembled in a narrow space, such as about ten or more to the inch.

The object of the invention is to devise a process of fabrication of an electrical unit which consists in the forming of a base element of thin insulating material, drilling holes at predetermined locations across the surface thereof, then with the aid of a mask spraying one side of the element to deposit molten metal thereon forming lines passing through some of the holes and forming metallic areas around others, with the metal entering the holes to coat the walls or sides thereof; then, with the aid of another mask spraying the opposite side of the element to deposit molten metal forming lines transverse to the first lines, said spray also entering the holes. In this manner a commutator element is formed with conductive strips on one side electrically connected through the deposited metal in the holes, with conductive strips on the opposite side of the element. By initially drilling holes at selected intersection points, a cross network is built up wherein one set of lines is electrically connected

2

to another set without employment of separate wires or connectors, and the entire assembly is no thicker than the sheet of base material plus the thickness of the sprayed lines on the opposite sides of the element.

Satisfactory results have been obtained by employing a thin sheet of laminated phenolic material about 0.020 of an inch in thickness sandblasted to form a good adhering surface. Molten zinc is first sprayed through a mask to form lines which have a good affinity with the base, and then molten copper is sprayed through the same mask to adhere to the zinc lines.

While the unit formed by the herein described process consists of a commutator unit, other electrical units may be fabricated by the same process without departing from the spirit of the invention.

Other objects of the invention will be pointed out in the following description and claims and illustrated in the accompanying drawings, which disclose, by way of example, the principle of the invention and the best mode, which has been contemplated, of applying that principle.

25 In the drawings:

Fig. 1 is a view of the base element shaped and drilled in accordance with a specific cross connecting pattern.

Fig. 2 is a view of one side of the element with the conductive metal sprayed thereon.

Fig. 3 is a view of the opposite side showing the arrangement of the lines thereon.

Fig. 4 is an enlarged section on lines 4—4 of Fig. 2 showing the manner of spacing a plurality of units.

Fig. 5 is a section on lines 5—5 of Fig. 2.

The electrical unit consists primarily of a thin sheet of insulating material 10 blanked out from a plate of laminated phenolic material about 0.020 inch thick, the particular material varying with the requirements with respect to insulating qualities, rigidity, ease of machining, etc.

After the sheet 10 has been blanked out to the outline of Fig. 1, holes 11 are drilled along the upper and lower edges and also holes 12. By means of a template or guide, smaller holes 13 are drilled in varying positions to conform to a predetermined connection pattern. Thereafter, the opposite surfaces of sheet 10 are sandblasted to remove any gloss on the surface and within the perforations. If, however, the material employed has a naturally dull finish, the sanding step is not necessary. As a next step, a mask is placed over the face of sheet 10 having openings therein forming the pattern of lines and

circles as in Fig. 2, and through such openings in the mask a spray of molten zinc is directed against the sheet 10.

The spray enters into and surrounds the holes 11 and 13, adhering to the inner walls thereof, and upon removal of the mask the unit will have the appearance of Fig. 2 with the conductive lines 20 thereon. The mask after cleaning is replaced, and now a spray of molten copper is directed against the sheet to superimpose the 10 latter metal upon the zinc.

The steps of successively spraying the zinc and copper through another mask is then repeated on the opposite side to form the circuit pattern of Fig. 3 with lines 21, 22 and 23 thereon. It will be particularly noted that the metal spray coats the walls of the perforations from both sides so that there is a greater thickness of deposit on the walls than upon the plane surfaces and a good conductive path is thereby formed extending 20 through the holes.

Where several units are employed, they may be stacked as indicated in Fig. 4, where rods 15 passing through aligned holes 11 have nuts 16 to clamp the units together, with washers 17 providing the desired spacing. A rotary contactor 18 (Figs. 2 and 5) on shaft 19 has one arm traversing the ends of lines 20 and another arm traversing the arcuate line 21 on the opposite side of the sheet 10. Thus, with the contactor 18 positioned to contact any line 20, it electrically connects the hole position designated C (Fig. 2) through line 22, arc 21, connector 18 to the opposite side of the sheet 10, line 20, hole 13 and line 23 to one of the hole positions 9 to 0.

The contactor 18 may correspond to wiper 110 of Patent 1,976,617 wherein it is positioned to represent a value which can be read out by sending impulses to positions 9, 8, 7, etc. of lines 23 which, when one of said lines has a hole 13 communicating with the line at which contactor 18 is set, will extend to hole position C which is connected to a current responsive device.

The unit may also serve as an impulse distributor with contactor 18 corresponding to wiper 279 of the patent (Fig. 13) which rotates continuously. It has been found that the lines formed on the sheet in the manner described constitute a good surface over which a wiper, such as contactor 18, may be swept repeatedly. In this use of the device, current is supplied to position C and conducted through line 22 to arc 21 and contactor 18. As the contactor rotates, the lines 20 are successively connected to the current source and each in turn will conduct the current to its related hole 13 and therethrough to a connected line 23 and hole 11, which latter may be connected to suitable individual current responsive devices, such as magnets 77 or 223 of the patent.

While there have been shown and described and pointed out the fundamental novel features of the invention as applied to a single modification, it will be understood that various omissions and substitutions and changes in the form and details of the devices illustrated and in its operation may be made by those skilled in the art

without departing from the spirit of the invention. It is the intention, therefore, to be limited only as indicated by the scope of the following claims.

What is claimed is:

1. In combination, a plurality of sheets of insulating material, each having a series of digit representing conductive lines sprayed on one side thereof, means for stacking said sheets in spaced relationship, conductors, one for each different digit line, to electrically common the lines of like digital value on the several sheets, a second series of conductive lines on the opposite side of each sheet, variously connected through the sheets with digit representing lines on the first side of the sheet, and a contactor for each sheet each positionable across the face of the related sheet to contact with any one of the second series of lines whereby current applied to any of the series of digit lines will be conducted to all contactors standing on a line of the second series that has electrical connection with said digit line.

2. In combination, a plurality of sheets of insulating material, each having a series of digit representing conductive lines on one side thereof, means for stacking said sheets in spaced relationship, conductors, one for each different digit line, to electrically common the lines of like digital value on the several sheets, a second series of conductive lines on the opposite side of each sheet, variously connected through the sheets with digit representing lines on the first side of the sheet, and a contactor for each sheet each positionable across the face of the related sheet to contact with any one of the second series of lines whereby current applied to any of the series of digit lines will be conducted to all contactors standing on a line of the second series that has electrical connection with said digit line.
